PRESS PLATE SEAL

Roy M. Schultz, Chicago, Harvey L. Davis, Highland Park, and Arvid B. Anderson, Park Ridge, Ill., assignors to Bishop Freeman Co., a corporation of Illinois
Filed Sept. 19, 1966, Ser. No. 580,491
5 Claims. (Cl. 38—66)

This invention relates to garment steaming and pressing equipment and, more particularly, is concerned with a press plate assembly incorporating an edge seal to prevent objectionable escape of steam from between the edge of the press head and the edge of the press plate.

In garment pressing equipment, steam under positive pressure is fed to the press head and diffuses therethrough to exit in distributed relation through the contact face of the press plate. In current practice, the press plate may be interchanged at times to accommodate some special purpose plate. This removal and reseating of the plates leads to a problem of edge leakage because the head and the plate may not reseat in a sealing relationship leading to objectionable escape of steam during use which, in addition to the waste involved, can be a danger to the operator. Further, the head and the plate may not be of exactly the same configuration whereby leakage of steam between them occurs. Diffusion of the steam throughout the press head is desirable to insure proper distribution and dispersion of the steam exiting through the press plate, but such diffusion of the steam increases the tendency for edge leakage. Peripheral seal gaskets or other static type edge seals dependent upon resilient conformity and seating are not suitable as such resilient gasketing materials are frequently impaired by the high temperature and the steam. Additionally, static type or relatively immovable edge seals tend to take a set and upon reapplication seat differently upon the head casting, leaving a myriad of minute escape passages. Further, where the head and the plate are not of exactly the same configuration, such as due to warpage, a static type edge seal is relatively ineffective.

In accordance with the present invention, an improved edge seal is provided and is positioned between the removably mounted press plate and the press head to respond in the presence of steam under pressure whereby an effective edge seal is provided. Flexible stripping is mounted in circumambient relation underlying the press head and it presents an elongated free and movable edge responsive to the action of the pressurized steam to move into peripheral sealing engagement with the press head. That action facilitates the use of materials resistant to the steam and capable of repeatedly conforming to the contact surfaces of the head.

Other features and advantages of the invention will be apparent from the following description and claims, and are illustrated in the accompanying drawings which show structure embodying preferred features of the present invention and the principles thereof, and what is now considered to be the best mode in which to apply these principles.

In the accompanying drawings forming a part of the specification, and in which like numerals are employed to designate like parts throughout the same,

FIG. 1 is a perspective view of a garment steaming and pressing machine of the type to which the invention is directed;

FIG. 2 is a cross section through the press plate assembly and is taken on the line 2—2 of FIG. 1;

FIG. 3 is an enlarged fragmentary section similar to that of FIG. 2 and better illustrating the mounting and sealing action of the edge sealing means;

2

FIGS. 4 and 5 are enlarged fragmentary sectional views corresponding generally to that of FIG. 3 and illustrating modified embodiments of the invention; and

FIG. 6 is a plan corner detail illustrating the edge configuration of the flexible stripping at corner regions of the press head assembly.

Referring now to the drawings, a conventional type of steaming and pressing machine is illustrated in FIG. 1 as including a support 10 mounting a cloth padded buck 11 such as is adapted to have garments pressed thereon by means of a hingedly mounted press head assembly 13 which may be swung downwardly to engage the garments placed on the buck. Steam is fed to the head to emerge through its contact face as the head is brought into pressing engagement upon the buck.

The head is itself heated by the action of the steam. That contributes to the problem of edge sealing the head to a press plate such as plate 18. The press head assembly 13 is illustrated in FIG. 2 as comprised of a conventional press head and a press plate 18. The press head is comprised of a head casting 14 and an apertured head plate 15, the head casting 14 forming the top and side walls of a shallow steam distribution chamber 14S which is fed from a conduit 16 that discharges from heating chamber 14H and enters the distribution chamber 14S at its top. The head plate 15 spans the open bottom of the head casting and is usually removably fixed thereto to seal in sealed engagement and to serve, in the embodiments illustrated, as part of a circumambient mounting rim 17 that is to receive press plate 18.

In the embodiment illustrated in FIGS. 2 and 3, the press plate 18 is a perforate rigid metal element provided with an upwardly or rearwardly extending peripheral flange 18F and is removably disposed across the bottom of the press head in closely spaced relation to the head plate 15 to provide a very narrow steam distribution space 19. Press plate 18 is removably secured to the press head as by springs 18S connected to the press plate which extend over the top of the press head. The action of the steam in diffusing throughout the space 19 in conjunction with steam pressure acting in the space 19 increases the tendency towards edge leakage between the rim 17 and the press plate 18. In FIG. 3 space 19 has been exaggerated for purposes of illustration, i.e., the plate and head are shown more widely spaced than is the case where the confronting plate and head surfaces are truly complementary.

Flexible stripping 20 is mounted as by adhesive A to flange 18F to present an elongated bridging portion 20E underlying the rim 17 and fitting loosely in the distribution space 19 especially where the confronting plate and head surfaces are not truly parallel throughout. Where parallel, the seal contacts the peripheral edge of rim 17 such as at corner edge 17C and the lower face edge 17F to seal the head assembly against edge leakage when steam is present and acting to escape. Where the surfaces are not truly parallel, for example where the plate or head are warped, the steam pressure moves the bridging position 20E into a sealing relationship at 17C or 17F or both, when the steam is turned off, the flexible stripping tends to relax and to return to a position of rest such as is shown in dotted line in FIG. 3.

The invention is shown in FIG. 4 incorporated in an arrangement wherein a diffuser plate 21 includes arches 21A of the general type and orientation disclosed in Freeman Patent No. 2,880,529, the plate 21 being removable as part of a composite unit that includes a main press plate 18P, with there being a steam distribution space 19 between the diffuser plate 21 and the head plate 15. At its peripheral edge the diffuser plate 21 overlies an associated rearwardly extending peripheral flange 21F termi-

nating in an inwardly beaded lip 21L which is in turn embraced by an inwardly beaded lip 18L provided on the press plate flange 18F. The flexible stripping 20 lies between the head plate 15 and diffuser plate 21 to undergo a sealing action similar to that depicted in FIG. 3. The movement of the stripping against the corner or lower surface of the head rim is enhanced by the action of the steam passing through the arches 21A and then upwardly beneath the stripping.

A cushioned press plate structure, as shown in FIG. 5, may also be equipped with an edge seal in accordance with this invention. A cushioned press plate assembly is illustrated as including a flanged diffuser plate 21 having multidirectionally oriented arches 21A, a layer 22 of asbestos sheeting overlying the plate 21, a cushion layer 23 of nylon felt and a cover layer 24 of woven nylon cloth. Once again the flexible stripping 20 lies between the head plate 15 and the press plate to undergo a sealing action in the steam distribution space 19.

The flexible stripping 20 may be anchored in a variety of different ways, some of which are shown herein to facilitate more complete disclosure of the inventive concepts. In FIG. 3, the flexible stripping 20 is a separate element having one edge 20A positioned between the press plate flange and the head casting rim 17. In this form, as illustrated, the anchored edge 20A is secured to the press plate flange 18F as by adhesive A.

Alternatively, the stripping may be separately positioned and held by clamping pressure of a press plate flange. In the embodiment illustrated in FIG. 4, the anchored edge 20A of the flexible stripping is pinched within the beaded edge of the diffuser plate flange 21F. Finally, as illustrated in FIG. 5, the edges of at least some of the layers 22 and 24 are return folded about the edge of the diffuser plate flange 21F and the outer cover layer 24 is extended inwardly and around the lip 17 to present the free bridging portion 20E. The cushion layer 23 is anchored to the asbestos layer 22 as by stitching S. The return folded portions are secured, as by an adhesive, to the diffuser plate flange 21F, however leaving stripping 20 and bridging portion 20E free to move as has been described. While the anchored edge 20A is shown adjacent the rim 17, no effective seal is developed along this side wall region because the flange does not circumferentially abut the rim 17.

In any of the disclosed forms, the flexible stripping extends around the periphery of the press head rim to provide a substantially continuous effective edge seal which bridges the space between the head rim and the press plate. The stripping in the regions of the rounded corners of the rim is suitably sheared, as indicated in FIG. 6, to provide individually movable sealing and bridging portions 20F successively overlapping at adjacent edges to avoid any substantial linear gathering and wrinkling while still maintaining a continuous seal along the rim periphery such as at 17C and 17F. The sheared edge effect enables sealing surfaces to be developed throughout the length of the head rim contacted by the flexible stripping.

Even where the flexible stripping is porous such as of woven nylon cloth, it produces an effective edge seal

which prevents unimpeded discharge of steam between the plate flange and the rim. Any steam which may escape is substantially reduced in pressure and is diffused by the sealing stripping. Other forms of flexible stripping may also be used.

Thus, while preferred constructional features of the invention are embodied in the structure illustrated herein, it is to be understood that changes and variations may be made by those skilled in the art without departing from the spirit and scope of the appended claims.

What is claimed is:

1. In a press head assembly that includes a press head having a head plate through which steam is to be emitted and bounded by a circumambient rim and a press plate spanning said head plate in close relation theretwixen, an improved edge seal comprising flexible stripping positioned between the press head and the press plate, said flexible stripping being secured to said press plate and presenting an elongated movable bridging portion extending marginally inwardly of said press plate to seal against the rim of said head and to respond to steam under pressure to move into peripheral sealing engagement against said rim periphery.

2. In a press head assembly in accordance with claim 1 and wherein said press plate has curving peripheral regions and said flexible stripping, at such peripheral regions, has spaced slits interrupting and dividing the same into individually acting bridging portions successively overlapping at adjacent edges to maintain a continuous seal.

3. In a press head assembly in accordance with claim 1 and wherein said press plate includes a liner plate having a rearwardly directed flange and having a flexible cover sheet in return fold relation about said flange to sealingly abut against the rim and extending marginally inwardly to serve as the flexible stripping to move into sealing engagement against the rim periphery.

4. In a press head assembly in accordance with claim 1 and wherein said press plate has a rearwardly directed flange therearound to surround said rim and wherein said flexible stripping is a distinct and separate element having an anchored edge sandwiched laterally between said rim and said flange and having a movable bridging portion extending marginally inwardly between the press head and the press plate.

5. In a press head assembly in accordance with claim 1 and wherein said press plate has a rearwardly directed flange terminating in an internal beaded lip and wherein said flexible stripping is a distinct and separate element having an anchored edge clampingly retained within said lip and having a movable bridging portion extending marginally inwardly between the press head and the press plate.
